R. FRYER.
LOOPER FOR SEWING MACHINES.

No. 378,165.

Patented Feb. 21, 1888.

UNITED STATES PATENT OFFICE.

RICHARD FRYER, OF BROOKLYN, NEW YORK, ASSIGNOR TO A. G. JENNINGS & SONS, OF SAME PLACE.

LOOPER FOR SEWING-MACHINES.

SPECIFICATION forming part of Letters Patent No. 378,165, dated February 21, 1888.

Application filed May 5, 1887. Serial No. 237,176. (No model.)

To all whom it may concern:

Be it known that I, RICHARD FRYER, of Brooklyn, Kings county, New York, have invented new and useful Improvements in Sewing-Machines, of which the following is a full, clear, and exact description.

This invention relates to that class of sewing-machines in which two rows of stitches are formed simultaneously side by side.

10 The invention consists in a new construction of looper, as will be more fully herein-after set forth.

Reference is to be had to the accompanying drawings, forming part of this specification, 15 in which—

Figure 1 is a side view of a sewing-machine, partly in section, embodying my invention. Fig. 2 is an end view of same, partly in section, the section being taken on line *cc*, Fig. 1. 20 Fig. 3 is an enlarged detail view of my improved loopers, shown in the act of taking the thread from the double needle and throwing off the loops already formed, the cloth-plate and adjoining parts being in section. Fig. 4 is a similar view, but showing the loopers in 25 the act of distending the loops and tightening them on those previously thrown off. Fig. 5 is an enlarged detail face view of one of my improved loopers with the threads thereon, as 30 in Fig. 3. Fig. 6 is a detail plan view of part of the needle-plate, and Fig. 7 is a detail face view of my improved double needle.

A in the drawings is the frame of a sewing-machine.

35 B is the reciprocating needle-bar moved by ordinary or suitable means above the cloth-plate D.

The machine shown in the drawings is known as the "Willcox & Gibbs sewing-machine;" 40 but other styles of machines may be used in carrying out my invention, if desired.

The needle-bar B carries a double needle, E, on a single shank, *a*. Each of the two prongs *b b* on said shank has an eye and point and constitutes, in fact, a needle proper. The eyes on said prongs are on the same plane and also in the same line. (See Figs. 1, 3, and 4.) The prongs *b b* in each double needle may be placed at suitable distances apart. The same machine 45 can have several sets of such needles for making stitches close together or farther apart.

By having both prongs or needles proper on one shank the use of differently-spaced needles becomes possible. This would not be possible if each needle proper were inserted in its own socket in the needle-bar.

F, Fig. 6, is a removable needle-plate, which may be secured to the cloth-plate D by screws *d d*, and it is provided with slots *e e*, for the passage of the cloth-feeder, and with two holes, *f f*, for the passage of the prongs *b b* of the needle E. These holes *f f* are arranged on different plates F at distances apart corresponding to the distances between the prongs *b b* of different double needles E, so that when a 65 double needle is changed a needle-plate F may be used with holes corresponding to the width of the double needle. The bridge *f²* separates these holes *f f*.

To insure that the threads will make no cross or miss stitches, I place in some cases a guard or shield, *g*, on the under side of the bridge *f²*. As the needle E descends, the prongs *b b* pass on either side of the bridge *f²* and downwardly-projecting shield *g*, thereby preventing the threads becoming intercrossed. The holes *f f* may be in the cloth-plate D and not in a detachable plate F. The plate F, when used, may have merely the holes *f f* for the needles, and not the holes *e e* for the feed-dogs. 80 The needle E passes through the needle-plate F and between the two loopers G and H, which are carried below the cloth-plate D. The looper H is mounted on the end of the driving-shaft I, and the looper G is mounted on the end of 85 a shaft, J, journaled in the frame A. The shafts I and J are in exact line with one another, and are geared by means of the intermediate shaft, K, carrying spur-wheels *h i*, which gear into spur-wheels *j l* on shafts I and J, respectively. By this means the shafts I and J move the loopers G H, and yet have a space between them to allow for the slipping off of the loops.

The loopers have each a shank, *m*, which is 90 passed into the ends of the carrying-shafts and secured there by means of a set-screw, *n*. The loopers are formed each with two projections, *o* and *p*, preferably arranged at an obtuse angle to each other, as in Fig. 5. The projection *o* has a nearly straight edge, *q*, beveled up from the center on both sides, as best seen in Fig. 3,

and terminates in a long hooked point, *r*, which projects considerably to one side from the face *s* of the looper, Fig. 3. The hook *r* of each looper projects toward the other looper. The 5 projection *p* has a wide rounding bevel, *t*.

u u are two straight or nearly straight edges on the back of the loopers, (see Fig. 5,) over which the threads slip. The looper *G* is what I call a "left-hand" looper, and the looper *H* 10 a "right-hand" looper. In other respects they may be alike.

L is a spring-arm attached to the frame of the machine, and provided with two eyes, *v v*, through which pass the threads *w w* from 15 spools or bobbins. (Not shown.) The arm *L* acts as a give-and-take thread-guide to compensate for any unevenness that may be found in the threads wound upon the spools.

By making the loopers *G* and *H* with outwardly-bent hooks *r* and dispensing with any delivery-point I am enabled to bring the loopers and thereby the stitches closer together than has heretofore been done. This is of great advantage. In order to increase or diminish the distance between the rows of stitches, it is only necessary to move the loopers in the direction of the length of the shafts *I* and *J* and secure them in place by means of screws *n*, and then place a double needle *E* and needle-plate *F* of the required width in position, 25 which is a very simple operation.

It will not be necessary to explain to those

acquainted with sewing-machines how the loopers *G H* engage the loops, distend them, and then slip them off. In this respect they 35 act like the looper of a Willcox & Gibbs machine. They differ from it in having no delivery-point and in projecting the hooks *r* farther sidewise. The delivery-point in the old looper is so far within the projection of the 40 hub of the looper as to prevent two such loopers being used in one machine on close rows of stitches.

Having now described my invention, what I claim is—

1. The looper *G*, consisting, substantially as described, of the part *o*, having the hook *r*, which projects outward beyond the face *s* of the looper, and the part *p*, having the beveled portion *t*, and the parts *o* and *p*, having the 50 straight edges *u u*, as set forth.

2. The looper *G*, consisting, substantially as described, of the part *o*, having the hook *r*, which projects outward beyond the face *s* of the looper, and the part *p*, having the beveled portion *t*, in combination with the double needle *E*, having the two prongs *b b* and the single shank *a*, substantially as herein shown and described.

RICHARD FRYER.
